UNITED STATES PATENT OFFICE

127,026

DESIGN FOR A COOKY CUTTER

Fred E. Miller and Mollie Miller, Enid, Okla.

Application December 7, 1940, Serial No. 97,153

Term of patent 14 years

To all whom it may concern:

Be it known that we, Fred E. Miller and Mollie Miller, citizens of the United States, residing at Enid, in the county of Garfield and State of Oklahoma, have invented a new, original, and ornamental Design for a Cooky Cutter, of which the following is a specification, reference being had to the accompanying drawing, forming part thereof.

We claim:

The ornamental design for a cooky cutter, as shown.

FRED E. MILLER.
MOLLIE MILLER.
